UNITED STATES PATENT OFFICE.

GEORGE GORDON PICKING AND WILLIAM HOPKINS, OF BOW, COUNTY OF MIDDLESEX, ENGLAND.

STEAM OR OTHER PUMP.

SPECIFICATION forming part of Letters Patent No. 405,501, dated June 18, 1889.

Application filed March 27, 1888. Serial No. 268,720. (No model.) Patented in England June 10, 1887, No. 8,355.

To all whom it may concern:

Be it known that we, GEORGE GORDON PICKING and WILLIAM HOPKINS, engineers, subjects of the Queen of Great Britain, residing at 58 Bow Road, Bow, in the county of Middlesex, England, have invented certain new and useful Improvements in Direct-Acting Steam or other Pumps, (for which we have obtained a patent in Great Britain, No. 8,355, bearing date June 10, 1887,) of which the following is a specification.

Our invention relates to improvements in direct-acting steam or other pumps or apparatus employed for raising or pumping liquids, air, or gas; and it consists of a novel arrangement of double-acting twin cylinders, pistons, and steam-ports, whereby the pistons of both cylinders are automatically reciprocated and steam distributed to the alternate ends of each other cylinder by the movement of each piston without employing any slide or other valve to distribute the steam, as in pumps in present use, and without the addition of cranks, crank-shaft, fly-wheel, and other ordinary gear.

In carrying out our invention we place the cylinders side by side and make a set of steam and eduction ports in or about the middle of each cylinder leading to the respective ends of the other cylinder. The pistons are hollow and made somewhat longer than the stroke. The steam or other fluid pressure is led to the interior of each piston and is (by the movement of the piston passing the ports in the cylinders) conveyed to the respective ends of the other cylinder, thus causing an automatic and reciprocating motion of both pistons. The pumps in connection with these double cylinders consist (by preference) of two double-acting pumps cast together, with the respective suction and deliveries of each connected. The arrangement of ports and passages in the steam-cylinder may be modified, so that the interior of the pistons may be used for the purpose of exhaust instead of supply, and the present exhaust-ports may be used for steam; but preference is given to the arrangement of working shown by the drawings.

Figure 1 is a plan of a pair of steam-cylinders and pumps attached thereto. Fig. 2 is

a horizontal section of the cylinders and pistons on the line 1 2 of Fig. 3. Fig. 3 is a vertical section on the line 3 4 of Fig. 2. Fig. 4 is a vertical section of one of the steam-cylinders on the line 5 6 of Fig. 2. Fig. 5 is a horizontal section of the two steam-cylinders with the pistons removed. Fig. 6 is an enlarged end view of one of the pistons. Fig. 7 is a section on the line 7 8 of Fig. 9. Fig. 8 is a section on the line 9 10 of Fig. 9. Fig. 9 is a view of the under side of one of the steam-pistons.

a a' are the steam-cylinders. *b b'* are the pumps. *c* is the steam-pipe. *d* is the exhaust-pipe.

Referring to Figs. 6, 7, 8, and 9, *e* is the body of the piston. *ff* are the packing-rings. *g* is the piston-rod passing through a stuffing-box to the pump. *e'* is a smaller rod passing through the piston and serving to unite the ends *e² e²* and secure the packing-rings *ff*. *h h* are the steam-passages in the piston, and *i i* are the exhaust-cavities. *e³* is a steady-rib uniting the two ends. *e⁴* is a slot in the side of the piston to receive a screw or stud *e⁵*, Fig. 3, to prevent the pistons turning on their centers.

In Figs. 2, 3, 4, and 5 the steam and eduction passages are shown. *k* is the steam-inlet port in the cylinder *a* leading to the port *k'* at the front end of the cylinder *a'*. *l* is the steam-inlet port in the cylinder *a* leading to the port *l'* at the back end of the cylinder *a'*. *m* is the steam-inlet port in the cylinder *a'* leading to the port *m* at the front end of the cylinder *a*. *n'* is the steam-inlet port in the cylinder *a'* leading to the port *n* at the back end of the cylinder *a*. *o* is the eduction-port in the cylinder *a* and *o'* is the eduction-port in the cylinder *a'*, both eduction-ports leading, by means of the passage *d'*, Fig. 3, to the exhaust-pipe *d*. *p p* are small auxiliary passages to admit steam behind the piston after cushioning has taken place.

In the position of the pistons as shown by the drawings steam is entering by the pipe *c* and passage *c'* to the inside of both pistons. The cylinder *a* is full of steam, the piston in *a* being at rest. Steam is passing through the port *h*, *k*, and *k'* to the front end of the

piston in the cylinder a' . The exhaust-steam behind the same piston in cylinder a' is passing out by the port l' to the port l in the cylinder a and by the cavity i to the eduction-port o , passage d' , and pipe d . The steam thus drives back the piston in the cylinder a' , the piston in a remaining stationary until the piston in a' has completed its back-stroke. When the piston in a has completed its back-
stroke, steam is admitted in a similar manner to that above described through the port h in the piston in a' and through the port n' to the port n , behind the piston in a , the steam in front of the piston in a being exhausted through the ports m and m' , cavity i , eduction-port o' , and passage d' . The piston in a is thus driven forward, while that in a' remains stationary, and so on, the cycle of operations continuing as long as steam is admitted to the cylinders. The pistons are cushioned at each end of the cylinders by their overlapping the ports l' , k' , n , and m , and the pistons are again started on their return-stroke by means of a small supply of steam passing through the small channels pp , whereby total stoppage of the engine is prevented.

What we claim is—

1. The twin cylinders $a a'$, each having four ports, two at the middle leading to the opposite ends of the adjacent cylinder and two at the ends leading to the middle of such adjacent cylinder, a steam-inlet at the middle of and common to both cylinders, and a transverse exhaust-passage at the middle of and common to both cylinders, in combination

with the hollow pistons forming steam-chests open to the full pressure of steam inside thereof, said pistons having ports $h h i i$ and steam-cushioned at each end of the cylinders, as set forth, and a steam-port p at each end ⁴⁰ of each cylinder to supply steam behind the pistons after the steam-cushioning for the return-strokes of the pistons, substantially as described.

2. The twin cylinders $a a'$, having, respectively, the eduction-ports $o o'$ at the middle of their length, a transverse passage d' , under and common to both said ports, the ports $l l'$, $n n'$, $k k'$, and $m m'$, arranged diagonally, as described and shown, and the steam-pipe e , ⁴⁵ common to both cylinders, in combination with the hollow pistons serving as steam-chests, receiving the full steam-pressure inside thereof direct from the steam-pipe and steam-cushioned at each end of the cylinders, ⁵⁰ each piston having two end ports $h h$, located at opposite sides of a central longitudinal line, and exhaust-cavities $i i$ and a port p at each end of each cylinder to admit a small supply of steam behind the pistons after the ⁵⁵ steam-cushioning thereof for their return-strokes, substantially as described.

Dated this 6th day of March, 1888.

GEORGE GORDON PICKING.
WILLIAM HOPKINS.
